AIRPLANE CHECKER

Filed Aug. 24, 1926

FIG. 1.

FIG. 2.

Inventor

David B. Finlay

By *Lachman Bryant & Darby*
Attorneys

UNITED STATES PATENT OFFICE.

DAVID B. FINLAY, OF FRESNO, CALIFORNIA.

AIRPLANE CHECKER.

Application filed August 24, 1928. Serial No. 131,256.

This invention relates to game apparatus and more particularly to that type of apparatus used in playing checkers in which there is employed a game board having on one face a suitable design, together with a plurality of game pieces adapted to be moved across the face of the game board as desired.

An object of the invention is to devise a game in connection with, preferably, aviation, and which, for the purposes of identification is termed, "the airplane checker game".

Another object of the invention is to provide a game board having upon one face, a plurality of spaces, preferably rectangular, the boundaries of which are indicated by a series of equidistantly spaced substantially rectangular markings, several of the spaces having designs of a character to be herein-after more specifically referred to. At intervals around the outer edges of the game board, certain groups of spaces are provided with designs representing, preferably, a dirigible at rest, to indicate and represent a starting position for a player.

It is a further object of the invention to provide the ornamental face of the game board with designs of different and distinguishing characteristics. Moreover, each starting position is represented by a dirigible provided with a different scheme of colors which distinguish it from the dirigibles positioned at the several other starting positions upon the game board face.

Game pieces, preferably in the form of miniature airplanes, are provided for each player, the color schemes of each of the game pieces corresponding to the color scheme of its respective dirigible starting position design. That is to say, the dirigible representing a certain player's starting position and the game pieces belonging to that certain player, will each be provided with corresponding color schemes or effects.

In the drawings:

Figure 1 is a plan view of the playing face of the game board of this invention.

Figure 2 is a view of the several game pieces adapted to be employed in connection with the game board.

The game board.

In the drawing, wherein like characters of reference represent similar parts in the

several views, 10 indicates generally the game board. This board is divided into a series of rectangular spaces 11. There may be any number of these rectangular spaces or squares, dependent upon the size of the game board.

Arranged approximately centrally of each side of the board, and occupying several of the rectangular spaces 11, are the representations of dirigibles at rest. These dirigibles represent the starting positions for the several players, and it will be noted that starting position No. 1, which is indicated at 12, is provided with major color sections of red.

The major color section of the dirigible 13 at starting position No. 2 is blue.

Starting position No. 3, is provided with the representation of a dirigible 14 at rest, and provided with major color sections of black.

At 15, another dirigible representing starting position No. 4 is shown. Sections of the dirigible 15 are colored white. As shown the area of each starting position, 12 to 14 inclusive, is equal to that of two of the spaces 11.

In the upper left hand rectangular space 16 of the game board, there is shown the representation of an airplane on fire.

Likewise, in the rectangular space at the lower right hand corner of the game board, a similar burning airplane is shown at 17.

The designs occupying the rectangular spaces at the extreme upper right hand and lower left hand corners represent bursting shrapnel, these designs being indicated at 18 and 19 respectively.

Upon the central portion of the game board face are several designs representing clouds, these being shown at 20, 21, 22 and 23 in Figure 1.

The game pieces.

In Figure 2, the game pieces of this invention are shown in the form of miniature airplanes.

In the drawing, four playing pieces 26, 27, 28 and 29, severally colored to correspond with the colors of the dirigibles at the four starting positions, are illustrated.

From the above, it will be seen that each starting position, four of which are illustrated in the drawing, has a corresponding game piece in the form of a miniature air-

plane, which game piece or plane is provided with a color scheme corresponding to that of its respective starting position dirigible design.

Method of playing the game.

The game of this invention may be played by either two, three or four persons, preferably the latter. The game is more interesting and entertaining when played by four persons.

At the outset of the game, each player selects a game piece having a color scheme corresponding to the color scheme of the dirigible of his respective starting position.

For example, the player seated opposite starting position No. 1, selects game piece 26, which is provided with the color red corresponding to the color section of the dirigible at that starting position.

The player at starting position No. 2 selects game piece 27, which is colored blue, and so on, until each of the respective players has selected and placed at his starting position the proper game piece for that position.

The player at starting position No. 1, by employing any suitable chance device, such, for example, as dice, or a spinner having a numbered surface and a rotary pointer, is the first to start the game.

After manipulating the chance device, of whatever character it may be, he is allowed to move his game piece out from the starting position into another of the squares 11, the particular square being determined, for example, by the number indicated by the chance device which he has previously manipulated. Each move is along one of the lines formed by the markings 24. It will be seen that these lines extend diametrically and diagonally relative to each of the squares 11, as well as along the boundaries of each square.

For example, if the chance device should indicate 3, the player would be thereby enabled to move out from his starting position, the distance of three markings 24 along any selected one of the lines of such markings leading from the square 11 included in the starting position. He may elect between moving the game piece 26 directly across the board over either of the two spaces 11 abutting his starting position, toward the starting position of the player opposite him or he may move the game piece to the right or left, following the selected line of markings 24; but he must not move the game piece beyond the number of markings indicated by the chance device.

Every player, however, as he moves his game piece out from the starting position, must, at the end of his move, place the nose of his airplane upon the proper marking.

By so doing, the player indicates to the

other players, the direction in which his plane is traveling.

The players of pieces corresponding to starting positions 2, 3 and 4 successively follow the procedure outlined above for the first player.

It will be seen, of course, that the actuation of the chance device, controls the movements of the several game pieces, and, obviously, luck has a great deal to do with the position of a player at any time. That is to say, if a player draws a larger number than another, naturally, his game piece will progress more rapidly than those of the other players.

While the movements of the game pieces have been described as being controlled by the use of a suitable chance device of any desired character, obviously, rules might be made and agreed upon by the several players before the game is started to determine the exact move each player is allowed in his turn.

The object of each player in the game is to so move his game piece as to bring it into a space 11 which is occupied by the piece of another player, compelling the withdrawal of the last said piece from the board. The successful player in such a move scores one (1) point. If a player can move his game piece onto the area of the starting position of any opponent he is also credited with one (1) point toward game, but each player is only permitted to land on any of the starting positions once in a single game.

In playing the game the players individual judgment is exercised, as there is no indication on the board of any particular path of movement that must be followed. The only restriction upon the direction of movement of any game piece is that it must be initiated in the direction indicated by the portion of the game piece representing the nose of the airplane. A move may therefore be along a straight line extending diametrically or diagonally of the particular space or square 11 in which it originates and may extend through one or more squares, either on a straight or angular path, simulating the movements of an airplane in executing the maneuvers technically toward "looping the loop" or making a "turn".

The player whose game piece is the last to remain upon the board is returned the winner, and he thus obtains a credit of six points.

While one method of playing the game of this invention has been described, different games may readily be played with the appliance illustrated in the drawing.

As previously stated, it is not essential to the proper playing of a game, to employ a chance device to determine the moves of the players, since, obviously, a set of rules may accompany each game, which rules will de-

scribe in detail, the exact manner of play and the number of moves that a player is enabled to make in his proper turn.

I claim:

- 5 1. A game apparatus comprising a board having one face divided into a series of spaces by dot-like markings, the markings designating the boundaries of the several spaces forming lines extending in a plurality of directions from each of the spaces, certain of the spaces bearing indications of 10 obstacles or dangers incident to aviation, and a plurality of game pieces, individually representing airplanes, adapted to be moved 15 over said spaces on the aforesaid lines provided by the dot-like boundaries of the spaces.
2. A game apparatus comprising a board having one face divided into a series of rectangular-shaped spaces by dot-like markings, the markings designating the boundaries of the several spaces forming lines extending diametrically and diagonally of each space, certain of the spaces bearing indications of obstacles or dangers incident to 20 aviation, and a plurality of game pieces, individually representing airplanes, adapted to be moved over said spaces on the aforesaid lines provided by the dot-like boundaries of the spaces.
3. A game apparatus comprising a board having one face divided into a series of rectangular-shaped spaces, one of the spaces adjacent the middle of each edge of the board bearing a designation indicating a

player's starting position, and others of said spaces bearing indications of obstacles or dangers incident to aviation, and a plurality of game pieces, individually representing airplanes, adapted to be moved from said starting positions in various directions over the rectangular-shaped spaces, the selected direction of movement of each piece being indicated by the relation of the piece to the boundary of the space in which the piece is positioned.

4. A game apparatus comprising a board having one face divided into a series of spaces by dot-like markings, a plurality of the spaces adjacent the marginal edge of the board bearing designations indicating players' starting positions, and others of said spaces bearing indications of obstacles or dangers incident to aviation, the markings designating the boundaries of the several spaces forming lines extending in a plurality of directions from each of the spaces, and a plurality of game pieces, individually representing airplanes, adapted to be moved from said starting positions on the aforesaid lines provided by the dot-like boundaries of the spaces, the selected line and direction of movement of each piece being indicated by the relation of the piece to one of the boundary markings of the space in which the piece is positioned.

In testimony whereof I have hereunto set my hand.

DAVID B. FINLAY.
